UNITED STATES. PATENT OFFICE.

CARL STILL, OF RECKLINGHAUSEN, GERMANY, ASSIGNOR TO THE FIRM CARL STILL,
OF RECKLINGHAUSEN, GERMANY.

APPARATUS FOR QUENCHING, LOADING, AND SCREENING COKE.

Application filed September 2, 1921. Serial No. 497,981.

(GRANTED UNDER THE PROVISIONS OF THE ACT OF MARCH 3, 1921, 41 STAT. L., 1313.)

To all whom it may concern:

Be it known that I, CARL STILL, a citizen of the German Republic, and residing at Recklinghausen, Westphalia, Germany, have invented certain new and useful Improvements in Apparatus for Quenching, Loading, and Screening Coke (for which I have made application for Letters Patent in Netherlands on February 22, 1921, No. 18,117, and for which I have obtained the following patents: German Patent 312,196, November 26, 1914; Austrian Patent 78,215, September 3, 1917; British Patent 147,097, July 7, 1920; French Patent 520,098, July 9, 1920), of which the following is a specification.

My invention relates to modifications and improvements of the object of Patent No. 1,340,990 granted to Carl Still and Carl Wessel for a "coke oven plant," and is similarly to the said invention of the purpose to remove from a stationary coke quenching bench and to load into wagons or the like stored masses of coke in coherent piles, at the same time the coke being screened in a convenient manner.

The essential feature of my invention consists in the combination, with a substantially horizontal bench for quenching and storing coke discharged from coke ovens, of a car travelling along the outside of said bench and bearing means for scraping off coke masses from the bench and screening them while being loaded into wagons or cars, all as hereinafter described and claimed in the annexed claims.

For the purpose of explaining the invention one embodiment of the same is illustrated in the accompanying drawing, in which—

Fig. 1 is an elevational section of the apparatus along the line A—B of Fig. 2, and

Fig. 2 is a plane view showing a part of the bench along which the coke loading car travels.

In front of the battery of coke ovens *k* is arranged the quenching bench *l* of usual construction, namely a large, substantially horizontal platform on which the coke is quenched and stored after it has been discharged from the ovens; *h* represents such a heap of coke. On the side removed from the ovens *k* there is a channel *x*, covered with

a sieve to carry away the superfluous quenching water, and at a short distance from the channel, the surface of the quenching bench ends in the edge *z*. Along this edge, at the outside of the quenching bench, the coke loading car *a* travels, for example on rails *g* parallel to the longitudinal direction of the bench, so that it can be brought to any desired position along the length of the bench, where there happens to be a quenched heap of coke *h* ready for loading. On a second set of rails *g* parallel to the rails *g* travels the wagon *w*, which serves to transport the loaded coke. The travelling loading car *a*, in the form shown in the drawings, is also constructed as a wagon consisting of an iron framing *e* and a box or bunker *f* provided therein. The lower part of the box *f* contains an arrangement for easily emptying the contents, consisting of the flaps *p* and the chutes *u*. The framing *e* has at top a practically horizontal frame which consists of two transverse girders *g* and several longitudinal girders arranged between them. Between the girders *g* is a screen extending over the whole area of the bunker *f* and composed of a substantially horizontal piece *r* and an inclined piece *r*¹, directly attached thereto. The plane of the piece *r*, which forms the continuation of the surface of the quenching bench *l*, and the plane of the piece *r*¹ meet in an obtuse angle along the line *y*. At the lower end of the screen plane *r*¹ is attached a loading chute *v*, which serves to guide the coke into the wagon *w*. The screen bars *s* (see Fig. 2) which are arranged at right angles to the longitudinal direction of the quenching bench, preferably taper in plan, the wider ends being turned towards the oven battery *k* and the narrower ends towards the chute *v*. In this manner the spaces between the bars gradually increase in width from their beginning at the edge *z* of the quenching bench to the discharge side of the car *a*. On the extended ends of the girders *g* are arranged bearings *i* for a shaft *d*, on which two winding drums *t* are fixed. The shaft is driven through gearing *n* (Fig. 2) by a motor *m*, which may also drive the whole car on the rails *g*. When the shaft is driven, the winding drums *t* wind up two ropes *b* which are attached to a beam *c* acting as a scraper or

100
105

sweeper; thus the latter is pulled over the surface of the quenching bench *l* and of the screen plane *r*.

The apparatus is used by first bringing the car *a* along the rails *g* to that place where there is a heap *h* of quenched coke which is loaded; a wagon *w* for receiving the coke is preferably brought to the same position along the neighbouring rails *g*¹. The scraper 10 *c* on the quenching bench is then brought into such a position that, in relation to the car *a*, it lies behind the heap of coke *h*, embracing the latter in its whole breath. By driving the shaft *d* the scraper is pulled towards the wagon and moves the coke heap *h* as a whole in a coherent pile, first across the quenching bench *l* and then over the first piece *r* of the screen. Whilst the heap 15 of coke is passing over the screen *r*, the coke ash, which always collects at the bottom of the mass, and the greater part of the small coke separate and fall into the bunker *f*. The rest of the small coke remaining in the heap is removed as the advancing mass 20 of coke passes over the edge *y* and spreads over the adjacent inclined piece *r*¹ of the screen so that now the small coke contained 25 in the upper part of the heap of coke is free to fall on to the screen *r*¹ and can pass through into the bunker *f*. The separation 30 of the small coke, as the heap passes over the screen, is facilitated by the form of the spaces between the bars, the width of which continually increases in the direction of movement of the coke, because 35 the sticking of pieces of coke between the bars and thereby the choking of the screen is prevented, since these pieces which partially project through the spaces are drawn 40 forwards until they arrive at a sufficiently wide part of the space between the bars to fall through. The coke having been thus freed from all the small particles, falls 45 over the chute *v* directly into the wagon *w* and is ready for dispatch. When the heap 50 of coke *h* in being moved over the screen of the car *a* has been advanced so far that the scraper *c* has reached the screen plane *r* and is resting upon it; then the car *a* together with mass of coke brought on may be 55 displaced from its first position along the bench *l* at will, whereupon this coke can also be loaded in any other wagons positioned in some distance from the aforesaid wagon *w*. After the whole coke heap taken off by 60 the scraper *c* has been loaded into wagons, the travelling car *a* can be moved to another part of the coke quenching bench *l* to carry out the same work and so on, until finally 65 the bunker *f* is filled with small coke and ashes and must be emptied. This is done at a point on the track intended therefor by opening the flaps *p* and discharging the contents over the chutes *u*, whereupon the apparatus is again ready for use.

The advantages of the invention are considerable and manifold. The troublesome and expensive work of loading quenched coke by manual labour is substituted by mechanical means which perform the operation in a very short time; with modern coke ovens of considerable output, this is of importance. The several heaps of coke discharged from a plurality of coke ovens can be stored on the bench after quenching as 70 required and removed and loaded in any succession at will, quite independently from the operation of the single coke ovens. The apparatus itself is simple and can be made without high costs, and, what is of considerable advantage, it can be applied to existing coke quenching benches of ordinary construction without difficulty and special provision. The coke thus loaded is sufficiently cleaned in the simplest manner from small 80 coke, which is not possible with manual treatment; moreover, there is combined with the immediate loading up of the larger coke, the simultaneous collection of the small coke, in such a manner that even this part of the 85 coke can be supplied to any particular place of use without difficulty.

Having thus described my invention, what I claim is:—

1. An apparatus for quenching, loading and screening coke comprising in combination a substantially horizontal stationary bench for quenching and storing coke discharged from coke ovens, a car adapted to travel along the outside of said bench, a screen arranged on top of the car in the continuation of the quenching bench plane, a chute attached to the screen and a mechanically driven scraper or sweeper operated from the car and adapted to move a mass of coke in a coherent pile across the bench, over the screen and toward the chute attached thereto.

2. An apparatus for quenching, loading and screening coke comprising in combination a substantially horizontal stationary bench for quenching and storing coke discharged from coke ovens, a car adapted to travel along the outside of said bench and containing a bunker, a screen arranged on top of the car in the continuation of the quenching bench plane, said screen covering the aforesaid bunker, a chute attached to the screen and a mechanically driven scraper or sweeper operated from the car and adapted to move a mass of coke in a coherent pile across the bench, over the screen and toward the chute attached thereto.

3. An apparatus for quenching, loading and screening coke comprising in combination a substantially horizontal stationary bench for quenching and storing coke discharged from coke ovens, a car adapted to travel along the outside of said bench, a screen arranged on top of the car and

formed of two planes meeting in an obtuse angle along a line parallel to the longitudinal direction of the quenching bench, the one screen plane forming a practically horizontal continuation of the quenching bench plane and the other screen plane adjoined to the first, forming a chute, and a mechanically driven scraper or sweeper operated from the car and adapted to move a mass of coke in a coherent pile across the bench, over the screen and toward the chute attached thereto.

4. An apparatus for quenching, loading and screening coke comprising in combination a substantially horizontal stationary bench for quenching and storing coke discharged from coke ovens, a car adapted to travel along the outside of said bench, a screen arranged in the top part of the car, a chute attached to the screen and a mechanically driven scraper or sweeper operated from the car and adapted to cause a quenched heap of coke to move as a coherent mass across the bench and thereafter to pass over the screen and the chute attached thereto.

5. An apparatus for quenching, loading and screening coke comprising in combination a substantially horizontal stationary bench for quenching and storing coke discharged from coke ovens, a car adapted to travel along the outside of said bench, a screen arranged on top of the car in the continuation of the quenching bench plane, a chute attached to the screen and a mechanically driven scraper or sweeper operated from the car and adapted to cause a quenched heap of coke to move as a coherent mass across the bench, and thereafter to pass over the screen and the chute attached thereto.

6. An apparatus for quenching, loading and screening coke comprising in combination a substantially horizontal stationary bench for quenching and storing coke discharged from coke ovens, a car adapted to travel along the outside of said bench and containing a bunker, a screen arranged in the top part of the car, said screen covering the aforesaid bunker, a chute attached to the screen and a mechanically driven scraper or sweeper operated from the car and adapted to cause a quenched heap of coke to move as a coherent mass across the bench, and thereafter to pass over the screen and the chute attached thereto.

7. An apparatus for quenching, loading and screening coke comprising in combination a substantially horizontal stationary bench for quenching and storing coke dis-

charged from coke ovens, a car adapted to travel along the outside of said bench and containing a bunker, a screen arranged on top of the car in the continuation of the quenching bench plane, said screen covering the aforesaid bunker, a chute attached to the screen and a mechanically driven scraper or sweeper operated laterally from the car and adapted to cause a quenched heap of coke to move as a coherent mass across the bench, and thereafter to pass over the screen and the chute attached thereto.

8. An apparatus for quenching, loading and screening coke comprising in combination a substantially horizontal stationary bench for quenching and storing coke discharged from coke ovens, a car adapted to travel along the outside of said bench, a screen arranged on top of the car and formed of two planes meeting in an obtuse angle along a line parallel to the longitudinal direction of the quenching bench, the one screen plane forming a practically horizontal continuation of the quenching bench plane and the other screen plane adjoined to the first forming a chute, and a mechanically driven scraper or sweeper operated laterally from the car and adapted to cause a quenched heap of coke to move as a coherent mass across the bench, and thereafter to pass over the screen and the chute attached thereto.

9. An apparatus for quenching, loading and screening coke comprising in combination a substantially horizontal stationary bench for quenching and storing coke discharged from coke ovens, a car adapted to travel along the outside of said bench and containing a bunker, a screen arranged on top of the car over the bunker and formed of two planes meeting in an obtuse angle along a line parallel to the longitudinal direction of the quenching bench, the one screen plane forming a practically horizontal continuation of the quenching bench plane and the other screen plane adjoined to the first forming a chute, and a mechanically driven scraper or sweeper operated from the car and adapted to cause a quenched heap of coke to move as a coherent mass across the bench, and thereafter to pass over the screen and the chute attached thereto.

In testimony whereof I affix my signature in presence of two witnesses.

CARL STILL.
